UNITED STATES PATENT OFFICE.

WILLIAM J. CITRON, OF SAN FRANCISCO, CALIFORNIA.

METHOD OF AND APPARATUS FOR RECORDING AND EXHIBITING.

Application filed February 16, 1927. Serial No. 168,683.

This invention relates to a method of and apparatus for recording and exhibiting stock-quotations, election returns, and other similar transitory information.

5 The object of the invention is to combine a standard form of typewriter and a projecting lantern in such a way that strip of paper may be fed through the typewriter and written upon, and automatically and 10 with a minimum of delay said strip will be passed across the aperture of the projecting lantern and the data written thereon will be projected in a readable form upon a screen. A further object is to control the movements 15 of the strip of paper by the action of turning the platen roll on the typewriter. Another object is to so arrange the typewriter and projecting lantern relatively that a minimum of space separates the typewriter platen from the light aperture in the lantern, in order to reduce the time interval between recording and projecting, and to 20 otherwise save paper.

In the accompanying drawings are illustrated two different forms which my invention may assume.

Fig. 1 shows a vertical central sectional view of a preferred arrangement of the apparatus;

30 Fig. 2 shows a detail sectional view of the guide means in front of the condensing lens;

Fig. 3 shows a perspective view of the guide means for the strip of paper which 35 is arranged between the typewriter and the light aperture;

Fig. 4 shows a vertical sectional view taken on the line IV of Fig. 1;

Fig. 5 shows a front elevation of the 40 apparatus;

Fig. 6 shows a plan view in section and diagram of a modified arrangement of the apparatus.

In its preferred form the apparatus includes a base 10 upon which is arranged a 45 projecting lantern 11. This base carries a platform 12 on which is arranged a standard form of typewriter, 13. A roll of paper 14 is mounted at the front edge of the platform, 50 and is fed through a guide 15 beneath the typewriter, thence upwardly at the rear, where it passes under and over the platen roll 16 of the typewriter. From here the strip of paper passes downwardly to a guide 55 arranged upon the platform 12. This guide

as here shown includes a stationary plate 17 and a hinged plate 18, between which the strip of paper passes. Also included in this guide is an idler roll 19 journaled in slots formed in brackets 20 fixed to the stationary 60 plate 17. Suitable springs 21 are provided to pull the idler roll against the stationary plate, so as to apply friction to the strip of paper.

The strip of paper next passes through a 65 guide formed by the front of a lens barrel 24 and a window 25 hinged thereto, the lens barrel contains the usual condensing lens 26 and is fixed to the front of the lamp house. From this point the strip of paper passes 70 around a driving roller 27, which is operatively connected to the platen roller 16 by any suitable driving means, such, for example, as a flexible shaft 28, and such gearing 29 as may be necessary to insure equal 75 travel and uniform direction between the two rollers. The strip of paper is held in frictional contact with the roller 27 by a spring-pressed roller 30, similar to the idler 80 roller 19. The rollers 19 and 30 serve to 85 keep a desired tension on the strip of paper as it passes across the light aperture, and they permit of sufficient slack being left in the strip of paper between the platen roller 16 and the idler roller 19 so that the necessary travel of the platen roller endwise on the typewriter will not be interfered with.

At the proper distance in front of the condensing lens there is arranged a projecting lens 31 for projecting the rays of light 90 upon a screen suitably located. As shown in Fig. 1 the rays will be projected along an axis lying in a vertical plane with the median fore-and-aft line of the typewriter. This will of necessity require the operator 95 of the typewriter to position himself to one side of the middle of the typewriter, so as not to obstruct the rays. This, however, is not inconvenient, since the smaller sizes of typewriters may be used and the strip of 100 paper written upon need be only 3 1/2 or 4 inches wide, hence cutting down the amount of travel of the carriage and platen of the typewriter. It is desirable, obviously, to reduce to a minimum the interval between 105 typing and projecting, and this I have accomplished in the above-described arrangement. In practice the strip of paper between the platen and the light aperture can be reduced to about 10 or 12 inches, so that there is

comparatively little delay between writing and projecting.

As an adjunct I provide a shelf 32, supported upon an arm 33 fixed upon a post 34, the latter being turnably mounted on the platform 12. This shelf is shown in Fig. 1 in full lines, where it is moved out of the way of the operator. The dotted line position shows the shelf extended over the platen 10 of the typewriter in position where the strip of paper may be passed from the platen over the shelf and thence to the projecting lantern. With the aid of this shelf the information to be projected can be written manually, as is sometimes desirable where the regular typist is temporarily absent.

In Fig. 6 I show a modified arrangement wherein the light is projected at right angles to the fore-and-aft line of the typewriter, 20 and thus the operator can take a position fully in front of the typewriter. This modification includes a 45° mirror A, arranged between the condensing lenses, and a similar mirror B, arranged in front of the condensing lenses. The strip of paper will be fed in the same manner as before, in front of the condensing lenses, but the matter written thereon will be projected in readable 25 form at one side of the typewriter.

30 Various changes in the construction and arrangement of the several parts may be employed, without departing from the spirit of my invention as disclosed in the appended claims.

35 Having thus described my invention, what I claim as new and desire to secure by Letters Patent is:

1. An apparatus for recording and exhibiting transitory information, comprising 40 a typewriter having a platen roll, a projecting lantern disposed below the typewriter, means for guiding a strip of writing material from a supply roll to the platen roll of the typewriter, means for guiding said strip 45 from the platen roll across the aperture of the lantern, and means connected with the

platen roll for advancing said strip past the aperture.

2. An apparatus for recording and exhibiting transitory information, comprising a typewriter having a platen roll, a projecting lantern disposed below the typewriter, means for guiding a strip of writing material from a supply roll to the platen roll of the typewriter, means for guiding said strip from the platen roll across the aperture of the lantern, means connected with the platen roll for advancing said strip past the aperture, and means for maintaining the strip under tension where it crosses the aperture, said means permitting slack to occur in the strip between the platen roll and aperture.

3. An apparatus for recording and exhibiting transitory information, comprising a typewriter having a platen roll, a projecting lantern disposed below the typewriter, means for guiding a strip of writing material from a supply roll to the platen roll of the typewriter, means for guiding said strip from the platen roll across the aperture of the lantern, means connected with the platen roll for advancing said strip past the aperture, and a shelf movable into position adjacent the platen roll, whereby the strip may be passed thereover in position to be written upon by hand.

4. An apparatus for recording and exhibiting transitory information, comprising a typewriter having a platen roll, a projecting lantern disposed below the typewriter, means for guiding and moving a strip of writing material from a supply roll beneath the typewriter, and thence upwardly around the platen roll of the typewriter, guide means adjacent the top of the lantern for frictionally guiding the strip, and means adjacent the lower portion of the lantern for moving said strip, said last-named means being operatively connected with the platen of the typewriter.

WILLIAM J. CITRON.
